DENTAL EQUIPMENT UNIT

Glenn C. McGouirk, 1105 W. Berry,
Fort Worth, Tex. 76110

Filed Sept. 15, 1966, Ser. No. 3,881

Term of patent 14 years

(Cl. D24—1)

FIG. 1

FIG. 2

FIG. 3

FIG. 5

FIG. 4

FIG. 6

FIG. 1 is a front view of the dental equipment unit embodying my new design;

FIG. 2 is a fragmentary isometric view of the unit of FIG. 1;

FIG. 3 is a top plan view partially shown in section;

FIG. 4 is a front view with portions fragmentarily shown;

FIG. 5 is a left side view of the unit of FIG. 1, and

FIG. 6 is a perspective view of the dental equipment unit as seen from the left of FIG. 2 with portions fragmentarily shown.

The broken lines are shown for illustrative purposes only.

I claim:

The ornamental design for a dental equipment unit, as shown and described.
